UNITED STATES PATENT OFFICE.

ALBERT G. SHANNON, OF SANTA ROSA, CALIFORNIA.

STENCIL-PRINTING MACHINE.

SPECIFICATION forming part of Letters Patent No. 257,521, dated May 9, 1882.

Application filed November 18, 1881. (No model.)

To all whom it may concern:

Be it known that I, ALBERT G. SHANNON, a citizen of the United States, residing at Santa Rosa, in the county of Sonoma and State of California, have invented certain new and useful Improvements in Stencil-Printing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a stencil-printing machine in which two cylinders are so arranged in a frame as to work against each other by means of cogs, and are fed by ink from the inside. Stencil or perforated paper from which it is desired to take impressions is placed around one or both cylinders, so that paper passing between said cylinders can be printed on one or both sides. The cylinders are perforated and partially filled with ink, but so 25 arranged (by smaller closely-fitting inside cylinders) that the ink can be turned off from either at pleasure. Therefore when one side only of a paper is to be printed the stencil from which the impressions are to be taken can be placed around one of the cylinders. The ink in the opposite cylinder should be shut off and an unperforated sheet placed around the same and held by means of the clamps thereon. A clean sheet of paper then passing between the cylinders will receive the impression from the cylinder carrying the stencil or perforated paper. If, however, it is desired to print both sides of a sheet at the same time with different subject-matter, perforated paper 35 can be placed around each of the cylinders, the ink turned on, and the paper moving between said cylinders necessarily receives the exact impression contained on the two stencils. A knife is placed on one cylinder, so as to cut 40 the paper at each impression or revolution of the cylinders.

Figure 1 is a perspective view of cylinder A, (containing inclosed cylinders A' and a,) having the encircling-cloth partially removed, so 45 as to show the parallel lines of holes through which the ink passes from the inner cylinders

that saturates the cloth. Fig. 2 shows in perspective the cylinders A' and a, A' being partially broken away, that fit within the cylinder A. Fig. 3 is a perspective of cylinder a. Fig. 4 is a cross-section through cylinders A A' and a combined; also showing the outlines of the reciprocating cylinder A² in contact. Fig. 5 is a longitudinal section of the combined cylinders in A, having a cloth covering, and the 55 cog-wheels on the end projections. Fig. 6 is a side elevation of the indented knife for cutting paper between cylinders. Fig. 7 is a perspective view of my improved press. Fig. 8 is a bifurcated handle, to be used, when desired, on cylinder A or A².

The cylinders A and A² have rows of holes b, which may be of any desired size or shape, running parallel with each other from one end of the cylinders to the other, leaving as much 60 space between the rows of holes as is occupied by the diameter of a hole.

A' is a cylinder having several parallel lines of holes, B, and is large enough to fit tightly inside of the cylinder A or A², in which it is placed. The large cylinders A and A² are alike 70 in function and construction, and therefore each contains the ink-regulating cylinders A' and a.

a is a cylinder, liquid-tight, either solid or 75 hollow, and fits loosely in A or A², and is designed to take up a portion of the space in said cylinders. d is a rod, which runs through and fits tightly in cylinders a and A', so as to cause them to turn with it, and also passes through 80 the extensions E E.

E is an extension of portion of each head of the cylinders A A², around which is fastened the cog-wheel F, and leaving space between the cog-wheels F and the cylinders A A² for an axle, and leaving space on the outside of the cog-wheel for a crank or wheel or other power to turn the machine. G is a handle at the end of the rod d, which turns the rod d and cylinder A', and is regulated by the scale C.

H are holes which are closed by a screwstopper, the head of each fitting flush with the surfaces of the cylinders.

I is a groove in the cylinder A, running from one end to the other.

K represents springs, to be used to fasten the stencil-paper that encircles cylinders A A².

The ends of said paper meet and are inserted into the groove I.

L is the covering, of cloth or other substance, fitting around the cylinders A A². The cloth

5 L is held firmly around and against the ends of the cylinders by screws J and springs K. The springs K are fastened at their inner ends in the groove I. They are flat and extend outward, and have a right-angled projection, which 10 gives the spring a T shape. Said spring fits closely against the ends of the stencil-paper, the paper being inserted under the springs, by which means it is secured to the cylinder.

M is the frame in which the machine works.

15 N represents grooves in which the ends of the cylinders A and A² work when placed in the frame M.

O is a set-screw that fits against the axle to regulate the pressure of the cylinders one 20 against the other.

P represents a roller fitting in frame Q, around which a roll of paper is placed.

Q is a frame fastened to the frame M.

25 R is a knife with sharp indentations on the edge, which may be fastened in the groove I.

If the two cylinders A A² be placed in the frame M, with axles in the grooves N, the cogs F fitting in each other, and a stencil-paper made by the electric pen or the needle typewriter patented by me November 1, 1881, and numbered 248,890, be placed around the cloth on cylinders A and A², and fastened by means of the springs K, and the handle G be turned on the graduated scale C so hole h be directly 30 under the hole H, the holes b will then be stopped by the solid portions of the interior surface of the cylinders A and A², and the holes B will be stopped by the solid portions of the cylinders A'. If printers' ink, softened 35

40 to the proper consistency by oil, be poured in holes H h, when in line, and the stoppers replaced, it will hold the same without leaking; and when the handle G is turned on the graduated scale C until the holes b come under the holes B the ink escaping through said holes is absorbed and equally distributed on the cloth covering the surface. The end of paper around the roller P is then placed between the cylinders A A², which are revolved by means of the power attached to the extension E, and the paper-stencil placed around each cylinder A A² will be copied on the sides of the paper passing between said cylinders. If the knife R be placed in the groove I in the cylinder A

so that the pointed edges will work in the 55 groove I of the cylinder A², the printed paper passing between the cylinders A A² will be cut off at each revolution of said cylinders.

The handle S, Fig. 8, may, if desired, be placed on the extensions E E of one of the 60 cylinders after the cog-wheels are removed, and the said cylinder, by means of this handle, may be rolled on the paper to be printed, making a copy of the stencil around it at each 65 revolution.

It is obvious that the two standards forming the frame Q may be set at any desired point on the side bars of the frame M, and that roller P can also be made a length to conform therewith. By this means a roll of paper of 70 any width can be used.

It must also be apparent that the uprights Q Q can be fixed to the ends of the frame M and the roller P constructed a conforming length.

Having thus described my invention, I claim 75 as new and desire to secure by Letters Patent—

1. In a stencil-printing machine, the cylinders A and A², having ink-receiving holes H, which are closed by screw-stoppers, said cylinders containing cylinders A', which are also provided with ink-receiving holes h, so arranged that the holes H and h can be placed in a direct line by means of the rod d, having the handle G, which is designed to be turned, when 80 desired, on the scale C, the latter indicating the relative position of the holes H and h, the perforations B b in the cylinders being so arranged as to be closed when H and h are opened, all substantially as described, and for the purposes set forth.

2. The cylinders A² A', having perforations B b, the former cloth-covered and provided with groove I, springs K, and knife R, in combination with cylinders A A', similarly perforated, covered, grooved, and provided with springs, the groove in cylinder A being adapted for the working of the knife R, and said cylinders A A² geared together and adjustably mounted on frame M, in the manner and for 85 90 95 the purposes set forth.

In testimony whereof I affix my signature in presence of two witnesses.

ALBERT G. SHANNON.
